UNITED STATES PATENT OFFICE.

CARL WARREN, OF SEBREE, KENTUCKY.

DITCHING-MACHINE.

1,239,650.

Specification of Letters Patent. Patented Sept. 11, 1917.

Application filed December 26, 1916. Serial No. 138,876.

To all whom it may concern:

Be it known that I, CARL WARREN, a citizen of the United States, residing at Sebree, in the county of Webster and State of Kentucky, have invented certain new and useful Improvements in Ditching-Machines, of which the following is a specification, reference being had to the accompanying drawings.

10 This invention relates to certain improvements in ditching machines and it is an object of the invention to provide a novel and improved device of this general character wherein the earth, after being loosened, is discharged at one side of the ditch being formed.

The invention also has for an object to provide a device of this general character with novel and improved guiding means for 20 automatically controlling the direction of travel of the machine during the digging or cutting of a ditch.

Furthermore it is an object of the invention to provide a novel and improved ditching machine including a vertically adjustable elevator upon which a digging implement discharges together with means whereby the elevator and the digging implement may be conveniently adjusted in either an 30 upward or downward direction.

The invention consists in the details of construction and in the combination and arrangement of the several parts of my improved ditching machine whereby certain 35 important advantages are attained and the device is rendered simpler, less expensive and otherwise more convenient and advantageous for use, all as will be hereinafter more fully set forth.

40 The novel features of the invention will hereinafter be definitely claimed.

In order that my invention may be the better understood, I will now proceed to describe the same with reference to the accompanying drawings, wherein—

Figure 1 is a view in top plan of a ditching machine constructed in accordance with an embodiment of my invention;

Fig. 2 is a view in side elevation of a 50 ditching machine as herein embodied;

Fig. 3 is a sectional view taken substantially on the line 3—3 of Fig. 2;

Fig. 4 is an enlarged view partly in top plan and partly in section illustrating a 55 means for operating the elevator;

Fig. 5 is a vertical sectional view taken

longitudinally of the machine as herein embodied;

Fig. 6 is a sectional view taken substantially on the line 6—6 of Fig. 2;

Fig. 7 is a fragmentary view in plan with a portion broken away of an endless conveyer as herein employed; and

Fig. 8 is a view in top plan of the plow or ground digging member as herein disclosed, detached.

As disclosed in the accompanying drawings, 1 denotes an axle to the opposite extremities of which are affixed the traction wheels 2, said axle 1 and wheels 2 rotating 70 in unison and in the same general direction.

Supported by the axle 1 and capable of swinging movement in a vertical direction are the side boards 3 arranged in predetermined spaced relation longitudinally of the axle 1 and which extend a desired distance rearwardly of said axle 1 and the traction wheels 2.

Extending between and rotatably supported by the opposite end portions of the boards 3 are the shafts 4 and 5 which have suitably affixed thereto adjacent the inner faces of the boards 3, the sprockets 6 around which are disposed the endless chains 7. The chains 7 are connected by the longitudinally spaced cross straps or bars 8 to which is suitably secured, as at 9, the apron 10, said apron 10 being of a width substantially equal to the space between the boards 3.

The upper shaft 5 extends beyond one of the side boards 3 and is operatively engaged, as at 11, with the short shaft 12 suitably supported by the adjacent side board 3. The forward portion of the shaft 12 has fixed thereto the beveled pinion 14 in mesh 95 with the beveled gear 15 loosely mounted upon the axle 1.

The gear 15 is provided with a clutch face 16 with which is adapted to coact the clutch member 17 suitably keyed to the axle 1 for 100 rotation in unison therewith but capable of movement longitudinally of said axle 1 under the influence of the operating lever 18 of a conventional type. It is thought to be self-evident that upon proper adjustment of 105 the clutch member 18 the apron 10 may be caused to travel or remain stationary.

I find it of advantage to position below the upper and lower stretches of the chains 7 the idle wheels 19 suitably supported by the 110 side boards 3 and which serve to hold against undue sagging the chains 7 and the apron

10 supported by said chains. Suitably supported by the upper or rear end portions of the side boards 3 is the conveyer frame 20 extending laterally of said side boards and 5 terminating at a predetermined point to one side of the machine.

Supported within the frame 20 is the endless apron 21 operatively engaged with the shafts 22 rotatably mounted adjacent the 10 opposite ends of said frame 20. The inner shaft 22 is extended forwardly beyond the frame 20, as is illustrated in Fig. 2 of the accompanying drawings, and is provided with the sprocket 23 around which is disposed the chain 24 which is also directed over a sprocket 25 suitably affixed to the shaft 12 whereby it will be at once noted that the apron 21 will be caused to operate in unison with the apron 10.

20 The apron 10 delivers upon the apron 21 and the apron 21 discharges at one side of the trench or the like being formed as is believed to be clearly apparent to those skilled in the art to which my present invention appertains.

The forward end portions of the boards 3 have interposed therebetween and suitably supported thereby the ground digging implement or plow 26 disposed on such an inclination as to discharge upon the upper stretch of the apron 10.

As is particularly illustrated in Fig. 8, the side marginal portions of the implement or plow 26 are defined by the upstanding flanges 27, and said side marginal portions are arranged in converging relation so that the earth as loosened by the implement or plow 26 will be discharged upon the upper stretch of the apron 10 at the transverse central portion thereof.

28 denotes an upstanding arch member suitably secured to the opposite end portions of the axle 1 and which bridges or extends across the side boards 3 and suitably secured, as at 29, to the arch 28 at a point substantially above the transverse center of the apron 10 is the tongue 30 of a length substantially equal to the length of the boards 3 and suitably secured to the forward end portion of the tongue 30 is the cross beam 31 extending an equal distance beyond opposite sides of the tongue 30. Operatively engaged with the opposite end portions of the beam 31 are the supporting wheels 32 preferably of a caster type. The wheels 32 are spaced one relatively to the other a distance in excess of the width of the ditch or the like to be formed and are adapted to travel upon the surface of the ground as is believed to be self-evident.

Interposed between the outer end portions of the beam 31 and the tongue 30 at a predetermined point rearwardly of the beam 31 are the brace rods 33. I also find it of advantage to interpose between the outer por-

tions of the axle 1 and the tongue 30 at a predetermined point in advance of the axle 1 the brace rods 34. I also interpose between the outer end portions of the axle 1 and the side boards 3 at a predetermined point in advance of said axle 1 the brace rods 35.

Loosely disposed through the tongue 30 at a point rearwardly of the beam 31 but in close proximity thereto is the vertically directed bar 36 having one of its side faces provided with the rack 37. The lower end portion of the bar 36 is operatively connected, through the medium of the curved arms or links 38, with the forward end portions of the boards 3 so that said boards 3 together with the implement or plow 26 may be raised or lowered through the influence of the bar 36.

39 denotes a casting suitably supported by the tongue 30 and through which the bar 36 is also directed, and rotatably supported within said casting 39 is the pinion 40 in mesh with the rack 37. The pinion 40 is carried by the stub shaft 41 extending exteriorly of the casting 39 and rearwardly of the beam 30 and has operatively engaged therewith through the medium of the knuckle joint 42 the operating shaft 43 which extends rearwardly of the tongue 30 and terminates in close proximity to the seat structure S supported by the tongue. The rear end of the shaft 43 is provided, as herein disclosed, with the hand wheel 44 whereby the requisite rotation may be imparted to the shaft 43 in order to raise or lower the bar 36 in accordance with the requirements of practice.

I also find it of advantage to have the upper end portion of the bar 36 loosely directed through the guide casting 45 supported in requisite position through the medium of the upstanding converging arms 46 suitably anchored to the beam 31 at opposite sides of the tongue 30.

Slidably engaged with the bar 36 below the tongue 30 is the sleeve 47 from which depends the frame 48 disposed transversely of the implement or plow 26. The opposite ends of the frame have rotatably supported therewith through the medium of a vertical axis the disks or rollers 49 which are adapted to contact with the side walls of the ditch or the like being formed so that the machine is properly and automatically guided during the digging of the trench.

The sleeve 47 moves downwardly by gravity but is adapted to be moved upwardly or elevated through the medium of the suitably guided flexible member 50 secured to the forwardly directed arm 51 carried by the sleeve 47 and which is also anchored, as at 52, to the beam 30 in close proximity to the seat structure S. When it is desired to elevate the sleeve 47 and the disks or rollers 49 it is

only necessary for the occupant of the seat S to pull upon the member 50.

Suitably affixed to the tongue 30 in advance of the seat structure S but in close proximity thereto is the double tree 53 provided at its opposite end portions with suitable means, as indicated at 54, whereby draft animals may be properly hitched to the machine. The tree 53 is of such a length as to extend a sufficient distance beyond opposite sides of the ditch or the like to be cut as to afford no hindrance to the draft animals hitched to the tree.

From the foregoing description, it is thought to be obvious that a ditching machine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A ditching machine consisting of a portable structure, an elevating mechanism supported by said structure and capable of rocking movement in a vertical direction, a ground digging implement carried by the forward end portion of the elevator, means coacting with the forward end portion of the elevator for raising or lowering the same, and a guide member carried by the last named means and capable of free vertical movement.

2. A ditching machine consisting of a portable structure, an elevating mechanism supported by said structure and capable of rocking movement in a vertical direction, a ground digging implement carried by the forward end portion of the elevator, means coacting with the forward end portion of the elevator for raising or lowering the same,

guide member carried by the last named means and capable of free vertical movement, and means for imparting upward movement to the guide member.

3. A ditching machine consisting of a portable structure, an elevating mechanism supported by said structure and capable of rocking movement in a vertical direction, a ground digging implement carried by the forward end portion of the elevator, means coacting with the forward end portion of the elevator for raising or lowering the same, a guide member carried by the last named means and capable of free vertical movement, said guide member including a frame, and disks carried by the opposite ends of the frame, said disks being rotatable about vertical axes.

4. A ditching machine consisting of a portable structure, an elevator supported by said structure and capable of rocking movement in a vertical direction, a ground digging implement carried by the forward end of the elevator, a vertically disposed bar operatively engaged with the forward end portion of the elevator, means for imparting endwise movement to said bar, a sleeve loosely mounted upon the bar, and a guide frame depending from said sleeve.

5. A ditching machine consisting of a portable structure, an elevator supported by said structure and capable of rocking movement in a vertical direction, a ground digging implement carried by the forward end of the elevator, a vertically disposed bar operatively engaged with the forward end portion of the elevator, means for imparting endwise movement to said bar, a sleeve loosely mounted upon the bar, a guide frame depending from said sleeve, an arm extending from the sleeve, and means engageable with said arm for moving the sleeve upwardly upon the bar.

In testimony whereof I hereunto affix my signature in the presence of two witnesses.

CARL WARREN.
